Louis S. Elsinger, Atlanta, Ga.

Application November 20, 1950, Serial No. 13,066

Term of patent 14 years

(Cl. D38—6)

To all whom it may concern:

Be it known that I, Louis S. Elsinger, a citizen of the United States of America, residing at Atlanta, in the county of Fulton and State of Georgia, have invented a new, original, and ornamental Design for a Combination Dog Collar and Leash Attaching Means, of which the following is a specification, reference being had to the accompanying drawing, forming a part hereof.

In the drawing:

Figure 1 is a front elevational view of a combination dog collar and leash attaching means showing my new design.

Figure 2 is an end elevational view.

I claim:

The ornamental design for a combination dog collar and leash attaching means as shown.

LOUIS S. ELSINGER.
